UNITED STATES PATENT OFFICE.

HARRY F. SMITH, OF DAYTON, OHIO, ASSIGNOR TO THE GAS RESEARCH COMPANY, OF DAYTON, OHIO, A CORPORATION OF OHIO.

METHOD OF AND APPARATUS FOR TRANSFERRING HEAT.

Application filed April 16, 1923. Serial No. 632,452.

This invention relates to heat interchange, and more particularly to the transfer of heat within a furnace, oven, or the like.

One of the principal objects of the invention is to provide an efficient method of heat transfer, and apparatus for carrying out that method; which method and apparatus is particularly applicable to a furnace, oven, or the like.

10 Another object of the invention is to provide a recuperator, for use with a furnace, or the like, which is simple in construction, particularly efficient in operation, and easy of maintenance.

15 Other objects and advantages of the invention will be apparent from the description set out below when taken in connection with the accompanying drawing.

In the drawing, in which like characters 20 of reference designate like parts throughout the several views thereof,

Fig. 1 is a vertical, transverse, sectional view through a furnace equipped with a recuperator constructed in accordance with 25 this invention;

Fig. 2 is a horizontal sectional view, on an enlarged scale, through the recuperator shown in Fig. 1, the section shown being along a plane indicated by the line 2—2 of 30 Fig. 1;

Fig. 3 is a fragmentary sectional view along the line 3—3 of Fig. 2, with certain parts in elevation;

Fig. 4 is a fragmentary sectional view 35 along the line 4—4 of Fig. 2;

Fig. 5 is an enlarged vertical sectional view of one of the recuperator tubes, shown in section in Fig. 4; and

Fig. 6 is a fragmentary sectional view 40 along the line 6—6 of Fig. 2.

The method of heat transfer embodied in this invention is generally applicable; but, as showing a preferred embodiment of apparatus for carrying that method into effect, it 45 is illustrated and described in connection with a recuperative furnace, or oven.

The furnace illustrated in the drawing is, in fact, a form of coke oven, adapted for so-called low temperature distillation. This 50 furnace consists of a body portion, designated generally by the numeral 10, which is built up of fire brick, or the like, in the conventional fashion. This furnace is so built up that it has a heating or distillation 55 chamber 11, provided with what may be

called a hearth 12, which constitutes the bottom wall of the chamber 11 and an arched top wall 13, this arch being made in the regular or conventional fashion. The chamber 11 is indirectly heated, by products of combustion which pass through a series of pipes extending transversely across the bottom of the chamber, one of these pipes being shown and designated by the numeral 15. Each of these pipes 15 is immersed in a lead bath, 60 which is designated generally by the numeral 16, the lead, during operation of the furnace being maintained above its melting temperature, and serving to float shallow pans, each of which contains a thin layer of 65 rather finely crushed material to be coked. As the pans are floated through the length of the chamber 11 the thin layer of coal in each pan is quickly brought up to the regular temperature and a predetermined amount 70 of volatile driven off therethrough, the temperature to which the fuel is subjected, and the length of time it is treated being dependent upon the character of coke desired. Of course this type of recuperator is entirely 75 applicable to any other type of furnace.

Extending downwardly through the walls of the furnace are a series of passages 20, the lower end of each passage receiving one upturned end of one of the pipes 15, the upper end of each passage being of smaller diameter, as designated by the numeral 21, and adapted to receive the fuel supply pipe 22, which is mounted in a hollow fitting 23, the passage through this fitting being in register, 80 and alignment, with the passage 21. Each of the fittings is provided with a flange 24, adapted to rest upon the brick work surrounding the upper end of the passage 21, to support the said fitting, and is provided 85 adjacent its upper end with a flange 25, which is adapted to receive and support part of the brick work. Each of these fittings 23 is positioned within an enlargement 30, at the outer end of each of the recuperator passages or chambers 31, which are provided in the upper part of the furnace structure, that part of the furnace structure which constitutes the recuperator. Extending transversely from the body portion of each of the fixtures 23 is a hollow extension 26, shown most clearly in Fig. 3, which is provided with two ports, properly shaped and properly positioned for each port to receive the opening in the downturned end 32, of one of a pair of 100 105 110

recuperator pipes or tubes 33, two pair of recuperator pipes being positioned within each of the passages 31.

Also provided in the walls of the furnace 5 are a plurality of passages 35, which are identical in construction with the passages 20, and of which the upper end is a smaller diameter passage 36 as in the case of the upper passages 21 already described. Each 10 of the passages 35 is also adapted to receive at its lower end an upturned end of one of the pipes 15.

As shown, particularly in Fig. 2, the extension 26 upon the fixture 23 associated with 15 one of the pair of recuperator tubes in the passage 31 extends in one direction, while the extension upon the fixture at the other end of the passage 31, associated with the other pair of recuperator tubes extends in 20 the opposite direction. Thus, as shown particularly in Fig. 2 the two pairs of recuperator tubes mounted in each passage 31 are associated with two of the pipes 15, each of 25 these pipes 15 being connected at one end to a passage 20, and thus to the recuperator tubes within that end of the passage 31, and at its other end to the passage 35, and thus to the space within the passage 31 surrounding 30 the recuperator tubes.

As shown in Figs. 1 and 2 each pair of adjacent passages 31 is connected, through the passage 39, which extends throughout the length of the furnace, with a stack or flue 40.

Each pair of recuperator tubes is connected 35 at its end opposite to the end which is connected to the fixture 23 to a second fixture 41, having a passage therein which opens into an air inlet pipe 42 each pair of 40 recuperator tubes being thus connected to a source of supply of air.

During operation of the device air is introduced through the pipes 42 into each of the recuperator tubes, and passes through 45 those tubes, and then through the fixture 23 into the passages 20. At the same time a combustible fuel is introduced through the pipe 22 and admixed with the air in the passage 20 to form a combustible mixture which 50 is burned, the hot products of combustion passing downwardly and thence across through the pipe 15, thence upwardly through the passage 35-36 into the passage 31 where they flow over the recuperator 55 tubes within that passage heating those tubes, and the walls of the passages, by convection then passing off through the flue or stack 40.

The arrangement is such that each recuperator passage has associated therewith 60 two pipes 15, each of which is connected at one end to one of the pairs of recuperator tubes, and at the other to stack. Consequently the hot products of combustion flow 65 in one direction through one pipe 15 and

one half of the recuperator passage and in the opposite direction through the adjacent pipe and the other half of the recuperator passage.

It has been discovered that while some 70 heat is transferred by convection from the hot products of combustion passing through the passages 31, and over the recuperator pipes therein, into the recuperator pipes, and from those pipes it is then transferred in 75 turn, by convection, to the fluid to be pre-heated which is passing through such pipes, a much greater quantity of heat is transferred to the walls of the passages 31, by convection, as the hot products of combustion flow therethrough, and then transferred by radiation from these walls to the recuperator tubes. For a given temperature differential the heat transferred by radiation 80 from the walls in the passages 31 to the recuperator tubes is very much greater than the heat transferred directly from the hot gases to the recuperator tubes by convection. 85

Preferably a plurality of plates 29, made up of some material which will readily receive heat by convection from the hot products of combustion and also of a material which is a good radiator of heat, is positioned, substantially parallel with the recuperator tubes, and thus substantially parallel with 90 the direction of the flow of the products of combustion through the passages 31, these plates being thus positioned to effect ready transfer of heat, by radiation, into the recuperator tubes. As shown, particularly in 95 Fig. 4, each passage 31, and each of the two sets of paired recuperator tubes positioned therein, is provided with four of these plates, two being positioned between the two tubes, and one between each tube and the 100 wall of the passage 31. Each of these plates has substantially twice as much surface exposed to the hot flue gases, to absorb heat by convection therefrom, as has the corresponding part of the wall of the passage 31. 110 Consequently the absorbing surface exposed to the hot products of combustion is very much increased, and the transfer of heat from the hot products of combustion by convection thus correspondingly increased. In 115 addition these plates are so positioned as to break up into streams the gases flowing through the passage 31 to effect more intimate contact between the gases and the surfaces to receive heat by convection. And 120 each of these plates in turn radiates heat to the recuperator tubes.

In order to facilitate transfer of the heat 125 which is imparted to the walls of the tubes to the air, or other fluid, passing therethrough, each tube has therein some perforated material, or body, such as wire screen, which is a good absorber of radiant heat, is constructed to present a large surface for contact with the fluid passing therethrough 130

and to break that fluid up into fine streams to effect intimate contact between the fluid and the surfaces. As shown, particularly in Figs. 4 and 5, each of these tubes is provided 5 with a centrally arranged partition 45 upon each side of which two layers of screen 46 are positioned, although this number may be varied as desired to give the most satisfactory results. It has been found, however, 10 that there is a very definite limit to the depth of penetration of the heat energy radiated from the tubes, and that beyond a certain point increasing the number of layers of screen is of little or no value. The partition 15 45 may be dispensed with but it both helps to maintain the screens in place and also tends to increase the efficiency of heat transfer. In arranging the screens care should be taken to not unduly interfere 20 with the transfer or flow of the air, or other fluid, through the recuperator pipe.

The partition 45 should, preferably, be opaque to radiant heat. This partition may be composed of heat resisting iron alloy, or 25 any other material which is opaque to radiant heat energy and adapted to withstand high temperatures. Each of these screens, and also the partition 45, receives heat by radiation from the heated recuperator tubes, 30 and also serves to break up the air, or other fluid, passing through the tube, and over the screens into fine streams, to thus effect intimate contact between the surface of these screens and the air. Furthermore these 35 screens present a large surface area for contact with the air to be heated by convection, and for a given temperature differential the heat transfer by convection from the screens to the air passing through the tubes is directly 40 dependent upon the heated surface with which the air is brought in contact. In addition it has been found that even though the temperature differential, and the surface of contact remain constant, a greater heat input from the screens into the air can be secured if the air is divided into fine streams 45 so that intimate contact is secured between the surfaces of the screens and the air.

In practicing this method of heat transfer, 50 using apparatus of the kind illustrated, or of similar character, the heat energy which is liberated when the fuel is burned in the presence of the oxygen of the air, or rather much of the heat energy that remains in the products of combustion after they leave the furnace chamber as flue gases, is transferred in part to the recuperator tubes, and in part to surfaces associated with those tubes, which surfaces are good radiators of heat. 55 These heated surfaces in turn transfer heat energy by radiation into the recuperator tubes. The heated recuperator tubes, of course, transfer some heat energy by convection into the air, or other fluid, passing 60 through them, but they transfer much more

heat energy into the screens by radiation. The screens then in turn function to very efficiently transfer heat by convection into the fluid passing thereover.

The screens illustrated constitute one very 70 satisfactory form of material for filling the recuperator tubes to receive heat energy by radiation therefrom and to transfer that energy by convection into the fluid passing through the tubes. But other material 75 may be used if desired. Finely spun glass wool, for example, would function very satisfactorily and any other type of material which is a good absorber of radiant energy, and which is so constructed as to expose a large surface of contact to the fluid passing therethrough, and to divide that fluid up into fine streams so as to bring it into intimate contact with the said fluid, 80 will function very satisfactorily.

While the method herein described, and the form of apparatus for carrying this method into effect, constitute preferred embodiments of the invention, it is to be understood that the invention is not limited to this precise method and form of apparatus, and that changes may be made in either without departing from the scope of the invention which is defined in the appended 85 claims.

What is claimed is:

1. In an oven of the character described, a combustion chamber, means for burning air and fuel to heat the interior of said chamber, a recuperator passage thru which the heated products of combustion pass to a stack or vent, said passage being arranged transversely of the combustion chamber, and having at each end an opening thru which the heated products of combustion enter the 100 said passage from opposite sides of said chamber; a burner element at each end of the passage, two recuperator tubes within said passage, the adjacent ends of said tubes being each provided with an air inlet, the opposite ends of said tubes being connected each respectively to one of the said burner 105 elements.

2. An oven of the character described 115 comprising a combustion chamber, means for burning air and fuel to heat the interior of said chamber, one of said burning means being located at each side of the oven; a recuperator passage extending transversely across said oven, and having at each end, an opening through which the heated products of combustion passing into the recuperator passage, said recuperator passage also having, substantially centrally thereof, an outlet opening connecting said passage to stack; a burner element, positioned within each end of the said recuperator passage, at which the air and fuel are burned to heat the said combustion chamber; and two recuperator tubes within said passage, each tube being 120 125 130

connected at its outer end to a burner element, and at its other end to an air supply.

3. In an oven of the character described, a recuperator comprising a pair of recuperator tubes, constructed for positioning within a recuperator passage, an air supply fitting associated with the said tubes, having a single inlet opening, and two outlet openings, each of said outlet openings being 10 adapted to cooperatively receive the opening in one of the recuperator pipes; and a burner element, having an offset extension thereon, said extension being provided with two openings therein, each adapted to receive 15 in register the open end of one of the pair of recuperator tubes.

4. In an oven of the character described,—with which is used preheating means comprising recuperative elements adapted to 20 readily absorb heat energy by radiation and to retransfer such heat energy by radiation the heat-absorbing and radiating parts of such preheating means being good absorbers and good radiators,—a recuperator passage, 25 a recuperator tube therein, a plate positioned within the passage, on each side of the tube and spaced from the wall of the tube and from the wall of the passage, each said plate being positioned to receive heat energy by 30 convection and to transfer heat energy therefrom to the recuperator tube by radiation.

5. In an oven of the character described,—with which is used preheating means comprising recuperative elements adapted to 35 readily absorb heat energy by radiation and to retransfer such heat energy by radiation the heat-absorbing and radiating parts of such preheating means being good absorbers and good radiators,—a recuperator passage, 40 a recuperator tube therein, a plate positioned within said passage on each side of the said tube each of said plates being spaced from the tube and from the wall of the passage and being positioned to receive heat energy 45 by convection and to transfer heat energy therefrom to the recuperator tube by radiation, and a radiant heat-energy-absorbing body within said tube.

6. In an oven of the character described,—50 with which is used preheating means comprising recuperative elements adapted to readily absorb heat energy by radiation and to retransfer such heat energy by radiation the heat-absorbing and radiating parts of 55 such preheating means being good absorbers and good radiators,—a recuperator passage having a pair of recuperator tubes therein, each of said tubes being connected at one end to a supply of gas to be heated and at the other end to a burner, and a plurality of 60 plates positioned within said passage and in heat-radiating relationship with the said recuperator tubes, each of said plates being positioned to receive heat energy by convection 65 and to transfer heat energy to its as-

sociated recuperator tube by radiation, there being one plate positioned between each tube and the corresponding wall of the said recuperator passage and two plates between the two tubes, the said plates being spaced 70 respectively from the tubes and from the walls of the said passage.

7. For use in a preheater, a recuperator tube, the outer surface of which is adapted to receive heat energy by convection and by 75 the absorption of radiant heat energy and the inner surface of which is adapted to transfer heat energy from the tube primarily by radiation, a partition within said tube which is opaque to radiant energy, and 80 a layer of screen within said tube upon each side of the said partition, which screen is positioned and arranged to absorb radiant heat energy radiated from the said recuperator tube and to also present a large surface area for contact with the fluid passing thru the said tube, and to divide said fluid into streams to effect intimate contact between the said fluid and the surfaces of the said screens. 85

8. In heat-transferring apparatus of the character described, a recuperator tube of heat-resistant material, and a perforated body positioned within said tube to receive heat energy therefrom primarily by radia- 90

9. In heat-transferring apparatus of the character described, a recuperator tube of heat-resistant material, and a plurality of 100 perforated partitions enclosed within said tube to receive heat energy from said tube primarily by radiation.

10. In heat-transferring apparatus of the character described, a recuperator tube of heat-resistant material which is substantially 105 rectangular in cross-section, and a perforated body of heat-resistant material positioned within said tube to receive heat energy therefrom primarily by radiation.

11. In heat-transferring apparatus of the character described, a recuperator tube of heat-resistant material, a perforated body of heat-resistant material positioned within 110 said tube out of substantial heat-conducting connection with said tube to receive heat energy from the tube primarily by radiation. 115

12. The method of transferring heat energy from a highly-heated fluid, to impart such heat energy to a fluid to be heated, which comprises imparting heat energy from 120 said highly-heated fluid to a heating body by direct contact of said heating fluid with said heating body, rapidly draining away from said heating body the heat energy being imparted thereto by the said highly-heated fluid by radiation to a second body, and rapidly draining from such second body the heat energy imparted thereto by radiation 125 from the heating body by passing in 130

intimate contact therewith substantially the entire quantity of fluid to be heated.

13. A recuperator tube for utilization in transferring heat energy from high-temperature gases flowing over the outside of the tube, and to impart heat energy to a gas flowing thru said tube to heat said gas to a high temperature, which comprises a tube of heat-resistant material, and a plurality of sections of wire screen composed of heat-resistant material positioned within said tube and out of substantial heat-conducting connection with said tube, to receive heat energy from the said tube primarily by radiation.

14. In an oven of the character described,—with which is used preheating

means comprising recuperative elements adapted to readily absorb heat energy by radiation and to retransfer such heat energy by radiation the heat-absorbing and radiating parts of such preheating means being good absorbers and good radiators,—a recuperator passage, a recuperator tube therein, a plate positioned within the passage between the tube and the wall of the passage, said plate being positioned to receive heat energy by convection and to transfer heat energy therefrom to the recuperator tube by radiation.

In testimony whereof I hereto affix my signature.

HARRY F. SMITH.
